United States Patent Office.

ADOLPH H. RAU, OF PHILADELPHIA, PENNSYLVANIA.

Design No. 2,657, dated May 21, 1867.

DESIGN FOR A SHAFT-FRAME.

The Schedule referred to in these Letters Patent and making part of the same.

TO ALL WHOM IT MAY CONCERN:

Be it known that I, ADOLPH H. RAU, of Philadelphia, county of Philadelphia, State of Pennsylvania, have invented or produced a new and original Design for a Frame for Holding Shafts; and I do hereby declare that the accompanying drawing, and the following explanation thereof, form a full, clear, and exact description of the said design.

The figure in the accompanying drawing represents a frame for holding shafts. Each of the side pieces of the frame consists of a vertical portion, *a*, and a bent portion, *d*, the vertical portions being connected at their lower ends by a cross-piece, *b*, and the bent portions being connected by a cross-piece, *c*. In the centre of the cross-piece *c* is an enlargement, *e*, for the passage of a vertical shaft, a hollow enlargement, *e'*, which forms a part of one of the standards or side pieces *a*, serving as a bearing in which a horizontal shaft may turn.

Claim.

The design for a frame for holding shafts, substantially as shown in and by the accompanying drawing. In testimony whereof I have signed my name to this specification in the presence of two subscribing witnesses.

ADOLPH H. RAU.
